FIG. 7.

UNITED STATES PATENT OFFICE.

FREEBORN F. RAYMOND, 2d, OF NEWTON, MASSACHUSETTS.

HEEL-NAILING MACHINE.

SPECIFICATION forming part of Letters Patent No. 410,196, dated September 3, 1889.

Application filed April 30, 1887. Serial No. 236,611. (No model.)

To all whom it may concern:

Be it known that I, FREEBORN F. RAYMOND, 2d, of Newton, in the county of Middlesex, and State of Massachusetts, a citizen of the 5 United States, have invented a new and useful Improvement in Heel-Nailing Machines, of which the following is a full, clear, and exact description, reference being had to the accompanying drawings, forming a part of 10 this specification, in explaining its nature.

The invention relates to a heel-nailing machine having a templet supported at the end of a lever and adapted to be moved toward the last or work-support to compress the heel-blank upon the outsole of the boot or shoe. 15

It further relates to a heel-attaching machine having a templet movable in relation to the heel-support, as above specified, in combination with the nail-driving devices.

20 It further relates to the templet movable in relation to the heel-support, as above specified.

It also relates to a templet movable as above specified, and a cam for operating or 25 moving it either directly or indirectly.

It further relates to various features of construction and organization, each of which will be hereinafter described.

In the drawings, Figure 1 is a view in vertical central section of a machine containing 30 my invention. Fig. 2 is a view of the revolving head. Fig. 3 is a view in plan of the templet and its lever or support. Fig. 4 is a vertical section taken through the templet. 35 Fig. 5 is a plan view of the nail-carrier. Fig. 6 is a view in front elevation of a portion of the post supporting the templet-lever. Fig. 7 is a view in vertical central section of a machine having the features of my invention, 40 showing the nail supplying and distributing device in elevation.

Referring to the drawings, A represents the frame of the machine.

a is the table, upon which slides the jack a', 45 which supports or carries the last or work-support a'.

B is the templet. It is mounted at the front end of the lever or pivoted holding-plate b in a manner to be removable therefrom. This lever or pivoted holding-plate is 50 pivoted at b' to a post or support b'', has the long arm b'', and is provided with movements

for moving the templet toward and from the last or work-support by the cam C upon the shaft c, the lever c', pivoted at c'', and connected by means of a cam-pin c' with the cam, and by means of the link c' with the links c' 55 c' of the toggle c'. The link c' of the toggle is connected with the slide-rod or connection c', which is guided in a suitable guideway in the bracket c'. The upper end of this slide rod or block is connected by means of an adjustable connection c' with the end of the lever or plate b. The adjustable connection shown comprises the two parts c' c'. The part c' 60 is connected by a link c' with the end of the lever b'. The part c' is the upper part of the slide block or rod c'. The continuous ends of the parts c' c' have screw-threads, which are opposed to each other, and each receives the 65 adjusting nut or connection c'. The cam is timed or constructed so as to provide the templet with any desired movement or movements in relation to the last or work-support. 70

Generally the movement will be as follows: Upon the starting of the machine the last or work-support, with the boot or shoe mounted thereon and with the heel-blank in position, is placed beneath the templet. The templet is 75 immediately swung downward to compress the heel-blank upon the outsole of the boot or shoe, and the heel-blank is held thus compressed during the forming of the awl-holes by the awls and the feeding of the attaching-nails and the driving of the same by the drivers. If the heel is to be blind-nailed, then the cam is constructed to move the templet away from the attaching heel-blank sufficiently to permit the top-lift plate, with the 80 top lift, to be inserted between the attached heel-blank and it, and it is then moved again to compress the top-lift plate and top lift so that the top lift is spanked upon the ends of the heel-attaching nails. If the attached heel 85 is breastested in the heel-attaching machine, the templet remains in place during the operation of the breastesting device, and it is then lifted to release the work. If it is not breastested, then it is lifted immediately after the attaching of 90 the top lift, to release the work. 95

Any suitable form of nail-carrier may be employed, and it may be operated by hand or automatically. I prefer that the nails be fed 100

automatically, and have represented a carrier not unlike that represented in my patent, No. 329,951, excepting that it is used for the main or principal attaching-nails instead of for the 5 auxiliary nails, as herein specified. D is the carrier. It is supported by the arm d of the revolving head D'. This revolving head is carried by the reciprocating head D², and is adapted to be automatically rotated by mechanism substantially as described in the Henderson and Raymond patent, No. 317,647, or in my pending application, or in the pending application of C. C. Small.

The revolving head has the arm d', which 15 supports a block carrying a gang or group of awls d², the arm d, above referred to, which also supports a block carrying a gang or group of drivers d³, and an arm d⁴, which may carry a breasting-knife. The arm d has a central 20 hole d⁵, which receives a post d⁶, attached to the nail-carrier. This post bears on a coiled spring d⁸, which tends to move it outward or away from the arm d. The drivers are carried by a block attached to the arm d, and 25 their ends enter the holes d⁹ of the carrier when the carrier is moved outward to its greatest extent from the arm d. (See Fig. 1.) The carrier D receives its nails from a suitable nail making and distributing machine E, (see 30 Fig. 7,) which is mounted upon a support e, so as to deliver nails to the carrier D when the head has been rotated sufficiently to bring the carrier beneath the nail making and distributing machine. The said nail making and 35 distributing machine E may be of any preferred construction and of the form of nail-feeding mechanism described in my various patents. The only distinction is, that the machines are organized to deliver nails to the 40 carrier D with heads lowermost instead of their points.

The carrier D has a perforated slide-plate d¹⁰, which slides in a dovetail recess in the carrier, and is automatically held thereon to 45 cover its holes by a spring d¹¹. This plate is moved to uncover the holes to permit the carrier to be supplied with nails when in its receiving position, the projection d¹² extending downward from the support e, so that as the 50 carrier D rotates into position the edge of the plate d¹⁰ comes in contact with it and is moved sufficiently to bring its holes in register with the holes of the carrier. Upon the rotation of the head D to bring the carrier into position 55 to deliver nails into the templet the spring d¹¹ automatically moves the slide-plate d¹⁰ to close the holes, and the plate remains in this position until the carrier is brought into position over the templet and is being moved 60 downward in relation thereto, when the edge of the plate is brought into contact with the projection d¹³ on the templet-support, which causes the slide-plate to be moved sufficiently to bring its holes in register with the holes of 65 the templet and the holes of the nail-carrier before the slide-plate is brought in contact with the upper surface of the templet, thereby

permitting the nails to leave the carrier and enter the holes of the templet.

The mechanism for rotating the head D' 70 is so timed that it turns the head a quarter of a revolution during each reciprocation thereof and stops with the nail-carrier D in position to receive nails from the nail-feeding device E. Consequently, upon the starting 75 of the machine the awls are in a position to be moved into place to register with the holes of the templet during the upper part of the downward movement of the cross-head D². This moves the drivers and nail-carrier 80 D into the position which the awls occupied before such movement. The next reciprocation of the head D² brings the nail-carrier D and drivers over the templet during the upper part of the downward movement of the 85 head, and as the head is moved downward the nail-carrier covering-plate d¹⁰ is moved and the holes of the carrier uncovered, so that the nails drop therefrom into the holes of the templet and the nail-carrier comes to 90 rest upon the upper surface of the templet. The head D², however, continues to descend, and the drivers then move in the carrier through it and into the templet, driving the 95 nails therefrom into the heel-blank and soles of the boot or shoe. Upon the upward movement of the cross-head the drivers are returned to their original position in relation to the carrier and the head rotated another quarter of a revolution to bring a breasting-knife adapted to be attached to one member 100 or arm of said head into position, and upon the next quarter-revolution of the head the carrier is moved into position beneath the nail-supplying mechanism E, the slide-plate 105 d¹⁰ moved to open its holes, and the nail-supplying mechanism set in operation to automatically feed nails to the holes d⁹ of the carrier.

I would say that this device for carrying 110 and driving the attaching-nails may be used without a templet for certain classes of work, in which event the nails would be delivered directly to the work and driven directly therein without the employment of any 115 additional templet than that provided by the holes of the carrier D. I would further say that I do not confine myself to the specific mechanism herein described for operating the templet-lever b. In lieu thereof, the lever or 120 pivoted plate or support b may be connected directly with an actuating-cam, as represented in Fig. 7.

By making the templet B movable in the manner specified a very powerful compressive force is obtained and one that can be utilized before the awls are caused to puncture the heel-blank.

Instead of forming the templet B as a separate block and detachably securing it to the 130 end of the lever or pivoted plate or support b, it may be formed in the end of the lever plate or support by drilling the necessary holes through the same.

I would here say that the heel-blanks and top lifts may be automatically fed into position between the templet and last or work-support, as described in my application filed 5 April 16, 1887, or in the application of C. C. Small, filed April 19, 1887.

The templet is constructed of such proportion and is so timed in its movements as not to interfere in any manner with the proper 10 operation of a breasting-knife mounted as hereinbefore referred to.

Having thus fully described my invention, I claim and desire to secure by Letters Patent of the United States—

15 1. In a heel-nailing machine, a rocking templet formed on or supported by a pivoted lever, plate, or jaw and provided thereby with a movement to and from the last or work-support, as and for the purposes specified.

20 2. In a heel-nailing machine, the combination of a last or work-support with a rocking templet B, mounted on or formed in a pivoted plate, lever, or support, and said pivoted plate, lever, or support adapted to have movement

25 imparted to its end to cause the templet to be moved toward and from the last or work-support, as and for the purposes specified.

30 3. In a heel-nailing machine, the combination of the last or work-support, a rocking templet B, mounted upon or formed in the end of a lever, and a cam connected with the end c³ of the said lever, as and for the purposes specified.

35 4. The combination, in a heel-nailing machine, of the last or work-support, a templet B, mounted upon a lever pivoted plate or support b, the cam C, and intermediate connecting mechanism, comprising the lever c',

40 the toggle c⁵, connected with and operated by the lever, the slide bar or block c⁸, and a link connecting the slide-block with the end of the said lever or support b, as and for the purposes specified.

5. The combination, in a heel-nailing machine, of the lever b, supporting at its end a templet having an arm b³, the slide-block c⁸, operated substantially as specified, and an intermediate adjustable connection between the slide-block and the end of the lever, substantially as described.

6. The combination of the lever b, supporting at its front end the templet B, the slide-block, and means, substantially as shown, for varying the line or point to which the templet B is moved, as and for the purposes specified.

7. The combination, in a heel-nailing machine, of a lever b, the templet B, supported thereby, the slide-head c⁸, and the connection 60 between the slide-head and the lever, comprising the parts c¹¹ c¹², having oppositely-arranged screw-threads formed upon their contiguous ends, and an adjusting-nut c¹⁰, as and for the purposes described.

65 8. The combination, in a heel-nailing machine, of the rocking templet B, having the movement in relation to the last or work-sup-

port specified, the last or work-support, and nail-driving devices, substantially as described.

70 9. The combination, in a heel-attaching machine, of a rocking templet B, pivoted to have movements in relation to the last or work-support imparted to it, substantially as specified, the last or work-support, and the nail-carrier D, substantially as described.

75 10. The combination, in a heel-attaching machine, of a rocking templet provided with a movement relative to the last or work-support, substantially as specified, the last or work-support, a gang or group of awls, the nail-carrier, and a gang or group of drivers adapted to be moved successively into operative position in relation to the templet, and then to be operated, substantially as specified.

80 11. The combination, in a heel-attaching machine, of a rocking templet provided with movements in relation to the last or work-support, as specified, said last or work-support, the nail-carrier D, and the gang or group 90 of drivers d³, substantially as described.

85 12. In a heel-attaching machine, the combination, with a suitable automatic nail-supplying apparatus, of a nail-carrier D, movable in the arc of a vertical ellipse from the nail-supplying apparatus to the point of driving, and whose holes are open when in its highest position and closed during the remainder of its rotation by devices set forth, and held closed until the time of driving, as described.

95 13. The combination, in a heel-attaching machine, of the rotary nail-carrier D, the slide-plate d¹⁰, spring d¹¹, and projection d¹³, substantially as described.

100 14. In a heel-nailing machine, a rotary nail-carrier D, having a horizontally-moving slide-plate for covering and uncovering the nail holes or apertures therein, controlled in its movements by mechanism as set forth, and adapted to be automatically opened when in its highest vertical position, automatically closed during its rotation, and again opened at the time of delivering, as described.

105 15. The combination of a reciprocating head D², carrying a rotary head D', the nail-carrier D, movable in relation to the arm d of the rotary head, as specified, the drivers d³, and the slide-plate d¹⁰, having a vertical and rotary movement and adapted to be moved to cover and uncover the holes of the carrier 110 D, as and for the purposes specified.

115 16. The combination, in a heel-attaching machine, of the reciprocating head D², the rotary head D', carried thereby, an arm d, supporting a gang or group of drivers d³, a 120 nail-carrier D, carried by said arm d, its hole-covering plate d¹⁰, adapted to be moved to uncover its holes to receive and discharge nails, and a suitable automatic nail-supplying apparatus, substantially as specified.
